CLAIM

The ornamental design for a pharmaceutical tablet, as shown and described.

DESCRIPTION

The file of this patent contains at least one drawing executed in color. Copies of this patent with color drawings will be provided by the Office upon request and payment of the necessary fee.

FIG. 1 is a front perspective view of a pharmaceutical tablet showing our new design;

FIG. 2 is a top view thereof;

FIG. 3 is a right side view thereof, with the left side view thereof being identical thereto;

FIG. 4 is a bottom view thereof;

FIG. 5 is a front view thereof, with the rear view thereof being identical thereto;

FIG. 6 is a cross-sectional view through section 6—6 of FIG. 1;

FIG. 7 is a front perspective view of an alternate embodiment of the design of FIG. 1;

FIG. 8 is a top view thereof;

FIG. 9 is a right side view thereof, with the left side view thereof being identical thereto;

FIG. 10 is a bottom view thereof;

FIG. 11 is a front view thereof, with the rear view thereof being identical thereto;

FIG. 12 is a cross-sectional view through section 12—12 of FIG. 7;

FIG. 13 is a front perspective view of an alternate embodiment of the design of FIG. 1;

FIG. 14 is a top view thereof;

FIG. 15 is a right side view thereof, with the left side view thereof being identical thereto;

FIG. 16 is a bottom view thereof;

FIG. 17 is a front view thereof, with the rear view thereof being identical thereto;

FIG. 18 is a cross-sectional view through section 18—18 of FIG. 13;

FIG. 19 is a front perspective view of an alternate embodiment of the design of FIG. 1;

FIG. 20 is a top view thereof;

FIG. 21 is a right side view thereof, with the left side view thereof being identical thereto;

FIG. 22 is a bottom view thereof;

FIG. 23 is a front view thereof, with the rear view thereof being identical thereto; and,

FIG. 24 is a cross-sectional view through section 24—24 of FIG. 19.

The grayscale shading in FIGS. 19—24 depict a color contrast, and is not indicative of any specific color.
